DRILLING APPARATUS

Dean Thrift, San Antonio, Tex.

Application December 14, 1936, Serial No. 115,716

14 Claims. (Cl. 255—72)

This invention relates to a drilling apparatus and has particular relation to that type of apparatus wherein the main drill is adaptable for use with a core barrel when it is desired to take a core, the present invention, however, embodying the type of main drill above referred to in combination with a core disintegrator, for disintegrating the core during drilling operations when a core or sample of a formation being penetrated is not desired.

An object of the invention is to provide a drill stem and drill whereby the bore may be formed, said drill having a central bore for the inlet of a core, with a core disintegrator adapted to be lowered into the drilling apparatus and seated in the main drill whereby the core formed by the drill may be destroyed.

It is another object of the invention to provide in the combination of drill and core disintegrator a construction whereby the cuttings formed while destroying the core may be washed out by the flushing fluid passing downwardly through the flushing channels of the drill.

It is another object of the invention to provide drilling apparatus of the character above referred to embodying a barrel, which may be lowered through or withdrawn from the drill stem, said barrel having cutters therein, preferably, though not necessarily, of the disc type, located within the barrel for destroying the core as it is formed and arranged at any selected elevation in the barrel, either adjacent the lower end of the barrel or at some other selected elevation.

The invention also embodies means for locking the barrel to rotate with the main drill.

It is another object of the invention to provide a novel method of destroying and removing a core left at the bottom of the bore by the main drill in the process of well drilling.

With the above and other objects in view, the invention has particular relation to certain novel features of construction, operation and arrangement of parts, and to a novel method, an example of which is given in this specification and illustrated in the accompanying drawing, wherein:

Figure 1 shows a vertical sectional view of the apparatus shown in operation.

Figure 2 shows a vertical sectional view showing the barrel in elevated position as being removed from the apparatus.

Figure 3 shows a fragmentary vertical sectional view taken on the line 3—3 of Figure 1.

Figure 4 shows a fragmentary vertical sectional view taken on the line 4—4 of Figure 5, and

Figure 5 shows a cross sectional view taken on the line 5—5 of Figure 4.

Referring now more particularly to the drawing, wherein like numerals of reference designate the same parts in each of the figures, the numeral 1 designates the drill stem which extends to the ground surface and to the lower end of which the drill 2 is attached. This drill may be of any conventional construction and has channels as 3, 3 through which the drilling fluid, delivered downwardly through the stem, may be discharged onto the drill cutters. The drill stem includes also the pin coupling member 4, the tubular coupling 5, the stem section 6 and the drill collar 7 to the latter of which the drill is attached. The pin coupling member 4 has the inwardly thickened outwardly threaded tapering pin 8 which is screwed into the coupling 5 as shown.

At its lower end the main drill 2 has a central bore 9, and opposing cutters 10, 10 are shown as extended inwardly and provided with the upwardly facing inside shoulders 11, 11.

There is a barrel 12 adapted to be lowered into and withdrawn upwardly through the drill stem. This barrel is preferably cylindrical in shape and when lowered into operating position its lower end will enter the bore 9 and seat on the shoulders 11 with its upper end fitting closely through the passageway through the pin 8.

The lower end of the barrel has the oppositely arranged lugs 12a adapted to enter correspondingly arranged notches 13 at the lower end of the barrel whereby the barrel will rotate with the drill. The upper end of the barrel is preferably of conical shape as at 14 and has the upstanding stem 15 which terminates in a conical shaped head 16 for a purpose to be hereinafter stated. The upper end of the barrel also has one or more openings as 17 to permit the entrance of the drilling fluid which may pass thence on down through the barrel.

Within the barrel are suitable core disintegrators, preferably in the form of rotatable cutting discs 18, 18. These discs are shown more in detail in Figures 4 and 5. They are mounted on suitable bushings 19, 19 which in turn are mounted on the transverse spindle 20 whose ends are suitably anchored to the barrel 12. These discs are spaced apart by the spacer 21 mounted on said spindle 20 and are spaced from the barrel by the spacers 22, 23, also mounted on the spindle. It will be noted from an inspection of Figure 5, that the discs are mounted at unequal distances from the axis of the barrel 12 so that

they will not track as the barrel rotates. They have the marginal edges 25, 26.

When a core or a sample of the formation is not to be taken the ordinary core barrel or core taking device will be withdrawn and the barrel 12 will be lowered into operative position. It may be dropped into position or may be let down through the drill stem by means of a cable 27 having a grappling tool 28 on the lower end thereof and engaged with the head 16. This grappling tool, if used, should be of the ordinary releasing type whereby it may be detached and withdrawn together with the cable. The barrel 12 should be, preferably, lowered while the drill 15 is elevated off of bottom and upon rotation of a drill the lugs 12a will drop into the notches 13 and thereafter the barrel will rotate with the drill.

As drilling proceeds a core 29 will be formed 20 and will enter the lower end of the barrel. Meanwhile drilling fluid will be forced under pressure down through the drill stem in the usual manner and will enter the openings 17 and pass on down through the barrel 12, but the pressure of the 25 drilling fluid against the upper end of the barrel will normally be sufficient to hold the barrel in operative position. When the discs 18 come into contact with the core 29 they will disintegrate the core. The barrel 12 is provided with openings 30 on each side, opposite the cutters 18, through which the cuttings of the disintegrated core may be washed by the drilling fluid out of the barrel 12 and said cuttings will pass on out through the channels 3 and will be returned up outside of the drill stem in the usual way.

The discs 18 are believed to be preferable although other type of disintegrators may be employed in their stead if desired, and they may be located near the lower end of the barrel or at 40 any other selected elevation in the barrel.

When it is desired to take a core the grappling, tool 28 may be lowered by the cable 27 and engaged with the head 16 and the barrel 12 removed and a conventional core taking apparatus 45 lowered in its stead into the drilling apparatus for sample taking purposes.

In some cases the discs 18 or other type of disintegrators used, may be dispensed with, particularly when soft formation is being drilled. 50 In such a case the drilling fluid forced, under pressure, through the barrel 12 will come into contact with the core entering the barrel with sufficient violence to wash out and destroy the core, the formation passing through a side opening or openings, such as 30 in the barrel and passing thence on down and out through the channels 3 and up through the bore on the outside of the drill stem.

The drawing and description disclose what is 60 now considered to be a preferred form of the invention by way of illustration only while the broad principle of the invention will be defined by the appended claims.

65 What I claim is:

1. Drilling apparatus comprising a tubular drill stem, a drill on the stem having an inlet for a core, a tubular barrel in the stem in alignment with the inlet, and core disintegrating means in the barrel.

70 2. Drilling apparatus comprising a tubular drill stem, a drill on the stem having an opening and a seat, a tubular barrel removably mounted in the stem with its lower end on the seat, core disintegrating means in the barrel arranged to oper-

ate against, and destroy, the core entering the barrel.

3. Drilling apparatus comprising a tubular drill stem, a drill on the stem having a central opening, a tubular barrel in the stem in alignment with the opening and having side openings and core disintegrating means in the barrel arranged opposite the side openings.

4. Drilling apparatus comprising a tubular drill stem, a drill on the stem having a lower end opening, a tubular barrel in the stem arranged to align with said opening, means for interengaging the barrel with the drilling apparatus to rotate therewith and core disintegrating means in the barrel.

10 5. Drilling apparatus comprising a tubular drill stem, a drill on the lower end of the stem having an approximately central lower end opening, a tubular barrel in the stem in alignment with said opening, means for interlocking the barrel 20 with the apparatus for simultaneous rotation, said barrel having a side opening and core disintegrating means in the barrel.

15 6. Drilling apparatus comprising a tubular drill stem, having a coupling member incorporated 25 therein, a drill on the lower end of the stem having a lower end opening, a tubular barrel fitted in closely through said coupling member and in alignment with the drill opening, said barrel having an upper end opening above the coupling 30 and core disintegrating means within the barrel.

7. Drilling apparatus comprising a tubular drill stem, a drill on the stem having a lower end opening and a discharge channel, a tubular barrel in the stem aligned with the lower end opening, core disintegrating means in the barrel, said barrel having a side outlet whereby flushing fluid passing downwardly through the barrel may discharge the disintegrated core through said side opening and through said channel.

40 8. In well drilling the method which consists in placing the drill upon the well bottom, causing the flight of a core disintegrator to the drill, operating the drill to leave the formation at the center of the well undisturbed by the drill and 45 simultaneously operating the disintegrator to remove said undisturbed formation.

9. In well drilling the method which consists in placing the drill upon the well bottom, causing the flight of a core disintegrator to the drill, operating the drill to form a core and to cause the same to enter the disintegrator and simultaneously operating the disintegrator to destroy the core.

10. In drilling wells by the rotary method, the 55 method of operation including the steps of introducing a core disintegrator into the upper end of the drill stem and moving it downwardly to operative position at the lower end of the drill stem, operating the drill stem and drill to disintegrate the formation at the bottom of the well, leaving the central portion of said formation undisturbed by the drill, simultaneously operating the disintegrator to remove said undisturbed formation.

11. In drilling wells by the rotary method, the method of operation including the steps of introducing a core disintegrator into the upper end of the drill stem and moving it downwardly to operative position at the lower end of the drill 70 stem, operating the drill stem and drill to disintegrate the formation at the bottom of the well, leaving the central portion of said formation undisturbed by the drill, simultaneously operating the disintegrator to remove said undis- 75

turbed formation, then removing the disintegrator upwardly through said stem from the well.

12. In drilling wells by the rotary method, the method of operation including the steps of introducing a core disintegrator into the upper end of the drill stem and moving it downwardly to operating position at the lower end of the drill stem, operating the drill stem to disintegrate the formation at the bottom of the well while leaving the central portion of the formation undisturbed thereby and simultaneously operating the disintegrator to disintegrate the undisturbed formation, meanwhile washing the cuttings of the disintegrator from the well.

13. Drilling apparatus comprising a tubular drill stem, a drill on the stem having an inlet for

a core and having an outlet channel for the drilling fluid, a tubular barrel in the stem in alignment with the inlet, said barrel having a side opening through which drilling fluid passing downwardly through the barrel may wash out the core entering the barrel.

14. In well drilling the method which consists in placing a drill upon the well bottom, causing the flight of a tubular barrel to the drill, operating the drill to form a core and to cause the core to enter the barrel, simultaneously forcing drilling fluid under pressure downwardly through the barrel to destroy the core and to wash the formation of the destroyed core.
